DISPLAY STAND FOR JEWELRY OR THE LIKE

Oskar A. Semler, 1817 Bayview Ave.,
Belmont, Calif. 94002

Filed Oct. 20, 1966, Ser. No. 4,352

Term of patent 14 years

(CL D80—9)

FIG. 1.

FIG. 2.

FIG. 3.

FIG. 4.

FIG. 2 is a top plan view thereof;

The dominant feature of my design resides in the portions shown in full lines.

I claim:

The ornamental design of a display stand for jewelry or the like, as shown and described.
